[57] CLAIM

The ornamental design for a chair, as shown and described.

DESCRIPTION

FIG. 1 is a perspective view from the front and to one side of the chair;

FIG. 2 is a front elevational view of the chair of FIG. 1; FIG. 3 is a side elevational view of the chair of FIG. 1; the opposite side being a mirror image thereof;

FIG. 4 is a rear elevational view of the chair of FIG. 1; the opposite side being a mirror image thereof;

FIG. 5 is a top plan view of the chair of FIG. 1; and,

FIG. 6 is a front perspective view from the front and to one side of a second embodiment of the chair of FIG. 1, the sole difference being the addition of different armrest members.

1 Claim, 3 Drawing Sheets
